T. J. FLEURY

COMBINATION LOCK

Filed March 5, 1923

FIG. 2.

UNITED STATES PATENT OFFICE.

THOMAS JOSEPH FLEURY, OF TORONTO, ONTARIO, CANADA.

COMBINATION LOCK.

Application filed March 5, 1923. Serial No. 623,043.

To all whom it may concern:

Be it known that I, THOMAS JOSEPH FLEURY, a subject of the King of Great Britain, and a resident of the city of 5 Toronto, in the county of York, in the Province of Ontario, Canada, have invented certain new and useful Improvements in Combination Locks, of which the following is the specification.

10 My invention relates to improvements in combination locks and the object of the invention is to devise a keyless lock applicable to doors, which provided the combination is known, can be opened from the outside with the minimum of trouble.

15 A further object is to devise means whereby by the turning of the knob in the reverse direction to the direction for the opening of the door, the lock will be reset.

20 A still further object is to devise means whereby the bolt can be freed to operate as a latch.

25 Another object is to devise means for preventing the lock being picked, and another object is to devise means whereby the combination can be readily changed without having to take the lock apart.

30 My invention consists of a combination lock constructed and arranged all as hereinafter more particularly described and illustrated in the accompanying drawing in which:

35 Fig. 1 represents a side elevation of a portion of the outside of a door showing my lock applied thereto.

Fig. 2 is a vertical section through the lock case.

Fig. 3 is a vertical section through the line 3—3 Figure 2.

40 Fig. 4 is a vertical section through the line 4—4 Figure 2.

Fig. 5 is a detail in plan showing the latch actuating means.

45 Fig. 6 is an elevational detail of a portion of the inside of a door showing the means for putting the lock on the latch and freeing the bolt so as to operate as a latch.

Like characters of reference indicate corresponding parts in the different views.

50 1 is the door which is provided with a rebate 2 extending inwardly from its outside face and adapted to receive the lock case 3 which is provided with a cover 4 secured thereto and held in place by means of the screw 5 extending through the cover plate into the post 6. 7 is a plate applied to

the outside face of the door and covering the exposed cover plate 4 of the lock case, said plate being held in place by means of the bolts 8 which extend through the door 60 and are provided at their inner ends with the nuts 9.

10 is the knob spindle which extends through the door, lock case, cover plate and plate 7 and is provided with the outer and 65 inner knobs 11 and 12. The spindle 10 is preferably of the ordinary rectangular cross section and extends through the pawl member 13 situated in the lock case, said pawl member 13 having the upper pawl 14 and 70 the lower pawl 15. 16 is a bolt receiving chamber situated in the vicinity of the lower end of the lock case 3 and having the orifice 17 in the exposed face of such casing. 19 is the bolt, slidably in the chamber 16, said 75 bolt having a cut-away upper portion 20 in the vicinity of its rear end adapted to receive the spring 21, the ends of which engage respectively the rear wall of the cut-away portion of the bolt and the rear wall 80 of the bolt receiving chamber 16. The rear wall of the chamber 16 has an orifice 22 positioned in the vicinity of the bottom thereof, through which the rear end of the bolt freely extends.

85 23 is a lever pivotally mounted intermediately of its length by means of the pin 24 in the lock casing 3. The lower end of the lever 23 is pivotally connected to the link 25 which is slidably connected to the 90 rear end of the bolt 19. 26 is a forwardly extending push arm pivotally connected to the upper end of the lever 23 and normally adapted to rest on the partition 27 formed in the lock case 3. 28 is an indenture in the partition adapted to receive the offset end 95 29 of the spindle 30 which extends inwardly through the lock casing and through the door, its inner end extending freely through the plate 31 secured to the inside face of the door. 32 is a knob provided on the inner end of the spindle 30 and having an offset arm 33 adapted to engage the respective indentures 34 in such plate. 35 is a spiral spring freely mounted on the spindle 30, its 100 outer end adapted to engage the collar 36 secured to such spindle and its inner end engaging the outer face of the plate 31.

105 37 are a plurality of vertical plates freely positioned in the casing side by side and 110 each having a forwardly extending slot 38. The rear face of each plate 37 is provided

with a rack 39. 40 are a plurality of disc members pivotally mounted on the spindle 41 secured in position in the lock case 3. 42 are tangentially extending portions 5 formed on the discs 40, said portions 42 being differently positioned for each disc, such portions 42 carrying the outwardly extending operating knobs 43 which extend through vertical slots 44 in the cover plate 10 4 of the lock case and into the stamped out portion 45 of the outer plate 7.

46 are depending dogs pivotally connected to radially extending lugs 47 on the discs 40. 48 are tension springs, each secured 15 at one end to the upper end of the corresponding dog and at the other end to the upwardly extending lug 49 on the disc 40. The lower end of each dog is provided with a tooth 50 which is adapted to engage the respective teeth of the ratchet 39 of the corresponding plate 37.

51 is a slide freely mounted in the lock case 3 on the stud 52, said slide being capable of forward and rearward movement 25 with respect thereto and its forward end connected by the links 53 to the lower ends of the dogs 46. 54 are a plurality of pawls pivotally mounted on the spindle 55 which is secured in position in the lock case 3, 30 each of said pawls being provided on its upper end with a tooth 56 adapted to engage the respective teeth of the corresponding plate 37. The lower ends of the pawls 54 are connected by means of the tension 35 springs 57 with the posts 58 formed on the upper end of the bolt chamber 16. 59 are links connecting the upper ends of the pawls 54 with the forward end of the slide 51.

60 is a plate hinged to the lever 23 in 40 the vicinity of its upper end and adapted to extend over the portions 42 of the discs 40 in order to prevent a wire or other tool being inserted into the slots 44 and up between the portions 42 against the arm 26 45 which would permit such arm to be raised and the door to be opened, as will hereinafter appear.

The lock case 3 is provided with an upwardly extending extension 61 with the vertical orifice 62 therethrough to permit vertical movement of the plates 37 thereinto.

63 is a screw extending through the plate 7, through the hole 64 in the wall of the casing 3 and into the wood of the door.

55 The operation of my device is as follows: When the door is to be latched instead of locked, this operation is achieved by turning the spindle 30 by means of the knob 32 into such position that its offset end 29 60 raises the arm 26, as is illustrated in dotted lines in Figure 2 and wherein the extremity of the arm 33 is in the vertical position, by turning the knob 11 in a counter-clockwise direction it will be seen that the pawl member 15 will be partially rotated

into engagement with the lower end of the lever 23 which will be pushed rearwardly, thus drawing in the bolt 19 against the action of the spring 21 and as the upper end of the lever 23 moves forwardly a corresponding extent the arm 26 will be permitted to be pushed forwardly thereby above the respective plates 37. This permits the bolt to be withdrawn the full extent and the door to be opened.

70 When the door is locked the knob 32 is turned so that the arm 33 lies substantially horizontal wherein the offset end 29 of the spindle 30 will be in the position illustrated in full lines in Figure 2 of the drawing, lying in the indenture 28 in the partition 27. This will permit the arm 26 to rest on such partition and if an attempt is made to rotate the spindle 10 by means of the knob 11 or in fact by either knob, 85 such knob if rotated in an anti-clockwise direction will merely actuate the lever 23 and the arm 26 until such free end of the arm comes into contact with the plates 37 which will not permit the withdrawal 90 of the bolt 19.

To unlock the door the knobs 43 are actuated, depending upon the particular combination or arrangement of the plates 37, it being understood that when a knob 43 95 is depressed, its attached disc 40 will be partially rotated and consequently the connected spring-held dog 46 will be moved upwardly and as such dog is in engagement with a tooth of the rack 39 of the corresponding plate 37, such plate will be moved up one tooth by each operation of a knob 43, the spring-held pawl 54 preventing retrograde movement of the lifted plate on release of the knob. When such knob is released into its uppermost position the tooth 50 of the dog slides down onto the next tooth of the rack 39 of such plate. Owing 100 to the different position of the slots 38 in the respective plates it will be seen that within limits, any desired combination can be achieved, thus for instance it can be arranged so that the first knob is only operated once, the second twice, and the third three times and the fourth, four times, in 110 which case it would take the corresponding number of operations to bring up any particular plate 37 so that its slot registers with the slots in the other plates. When the plates are moved up into such position that the slots all register, such slots will be opposite the arm 26 and by means of the knob 11, and the lever 23, such arm can be actuated so that its free end enters the registering slots 38, thus permitting the 115 bolt 19 to be withdrawn the full extent and the door opened.

To reset the lock it is only necessary to rotate the knob 11 or spindle 10 in the reverse direction to the actuating direction.

The pawls 14 will engage a downwardly extending lug 64 on the slide 51, thus moving said slide rearwardly and as such slide is connected by means of the links 53 and 59 with the dogs 46 and the pawls 54 respectively, such dogs and pawls will be withdrawn from the racks 39, permitting the plates 37 to fall into their initial position, which is illustrated in Figure 2.

10 It will be apparent that even without substituting new plates 37 the combination can be changed by merely removing the lock and changing over the respective plates.

From the above description it will be seen 15 that I have devised a simple and effective combination lock for use with doors, particularly the front doors on houses and other buildings, which will obviate the necessity of a key and which can be actuated by merely operating the respective knobs 43 to 20 achieve the desired combination.

What I claim as my invention is:

1. In a combination lock, the combination 25 with a casing door knob and door knob shank extending through the casing, of a series of independently movable parallel plates, a bolt guided in the casing, an operating lever pivoted in the casing and linked to the bolt at one end, a push arm pivotally 30 connected to the opposite end of the lever, means for independently adjusting the plates vertically located between the door knob shank and push arm, and a series of 35 movable knobs located exteriorly of the casing for independently operating each of such individual plate adjusting means.

2. In a combination lock, the combination 40 with the bolt and door knob, of connecting means between the knob and bolt for actuating the latter, manually operable selective combination means for permitting the actuation 45 of the bolt by the knob, said means normally preventing such actuation, and means actuated by the rotation of the door knobs in the reverse direction for resetting the selective combination means.

3. In a combination lock, a lock case, a 50 slidable bolt therein, a door knob spindle, a door knob thereon, a lever pivoted intermediate of its length in the casing and having one end connected to the bolt, means 55 for actuating the lever from the door knob

spindle, a forwardly directed arm connected to the other end of the lever, a plurality of independent vertically slidable plates arranged side by side in the lock case, each of 60 said plates having a cross slot therein disposed at a different height to the slots in the adjacent plates, and manually operable selective means for independently actuating the plates in a vertical direction to bring the respective slots into register.

4. In a combination lock, a lock case, a 65 slidable bolt therein, a door knob spindle, a door knob thereon, a lever pivoted intermediate of its length in the casing and having one end connected to the bolt, means for actuating the lever from the door knob spindle, a forwardly directed arm connected to the other end of the lever, a plurality of 70 independent vertically slidable plates arranged side by side in the lock case, each of said plates having a cross slot therein disposed at a different height to the slots in the adjacent plates, manually operable selective 75 means for independently actuating the plates in a vertical direction to bring the respective slots into register, and independent manually operable means for raising the arm out of engagement with the plates when 80 the latter are in the normal or locking position.

5. In a combination lock, a lock case, a 85 slidable bolt therein, a door knob spindle, a door knob thereon, a lever pivoted intermediate of its length in the casing and having one end connected to the bolt, means for actuating the lever from the door knob spindle, a forwardly directed arm connected to the other end of the lever, a plurality of 90 independent vertically slidable plates arranged side by side in the lock case, a rack on each of the plates, a plurality of independent members pivoted in the lock casing, operating knobs on the members, spring-held dogs pivoted on each of the members engaging the rack on the corresponding plate, a plurality of spring-held pawls pivoted in the lock casing and engaging the racks on the plates, and means actuated by the 95 rotation of the door knob in the reverse direction for releasing the dogs and pawls from the respective racks.

THOMAS JOSEPH FLEURY.
